US00D577117S

(12) **United States Design Patent**
Biener et al.

(10) **Patent No.:** US D577,117 S
(45) **Date of Patent:** ** Sep. 16, 2008

(54) **CONNECTOR TUBE**

(75) Inventors: **Achim Biener**, Aufkirchen (DE); **Bernd Christoph Lang**, Grafelfing (DE)

(73) Assignee: **MAP Medizin-Technologie GmbH**, Martinsried (DE)

(**) Term: **14 Years**

(21) Appl. No.: **29/268,229**

(22) Filed: **Nov. 2, 2006**

Related U.S. Application Data

(63) Continuation of application No. 29/224,841, filed on Mar. 9, 2005, now Pat. No. Des. 536,091.

(30) **Foreign Application Priority Data**

Oct. 1, 2004 (EP) 000233218

(57) **CLAIM**

The ornamental design for a connector tube, as shown.

DESCRIPTION

FIG. 1 is a perspective view of a connector tube according to our design;

FIG. 2 is a reverse perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
